FEEDING RACK FOR NEWSPAPER BALING MACHINES

Filed Oct. 30, 1929

2 Sheets-Sheet 2

UNITED STATES PATENT OFFICE

MORRIS F. BERG, OF LOS ANGELES, CALIFORNIA

FEEDING RACK FOR NEWSPAPER-BALING MACHINES

Application filed October 30, 1929. Serial No. 403,504.

My invention relates to a feeding rack that is especially designed for use in connection with flat newspaper baling machines and the principal object of my invention is, to provide 5 a relatively simple, practical and inexpensive rack that will receive and hold a pile or stack of flat laid newspapers and which rack, when manipulated, will quickly feed or deposit the stack of papers into the compression chamber 10 of a newspaper baling machine.

Further objects of my invention are, to generally improve upon and simplify the construction of the existing forms of newspaper feeding racks, further to construct the rack 15 so that it may be conveniently handled and manipulated by a single operator, and further, to construct the rack so that it may be conveniently moved from one point to another and shifted toward and away from the 20 baling machine during the transfer of a pile of newspapers from the rack into the compression chamber of the bale machine.

With the foregoing and other objects in view, my invention consists in certain novel 25 features of construction and arrangement of parts that will hereinafter be more fully described and claimed and illustrated in the accompanying drawings, in which:

Fig. 1 is a vertical section taken through 30 the center of a feeding rack constructed in accordance with my invention and showing the same in position to receive a stack of papers.

Fig. 2 is a vertical section similar to Fig. 1 35 and showing the positions assumed by the various parts of the rack when the stack of newspapers is straightened up for discharge from the rack into the baling machine.

Fig. 3 is a vertical section similar to Figs. 40 1 and 2 and showing the positions of the various parts of the machine after the stack of newspapers has been discharged from the rack into the baling machine.

Fig. 4 is a vertical section taken approxi- 45 mately on the line 4-4 of Fig. 3.

Fig. 5 is a horizontal section taken approxi- 50 mately on the line 5-5 of Fig. 3.

Fig. 6 is a vertical section taken on the line 6-6 of Fig. 3.

55 Referring by numerals to the accompany-

ing drawings, which illustrate a practical embodiment of my invention, 10, 10 designate the side rails of the base frame of the rack, the rear ends of which side rails are connected by an end rail 11 and the forward ends of 55 said side rails are supported upon an axle 12 and journaled upon the ends of the latter are small wheels 13.

One end of axle 12 is mounted in a bearing plate 13^a that is mounted for vertical sliding 60 movement in a bracket 13^b and the vertical position of which bearing plate is regulated by a set screw 13^c that is screw seated in the upper portion of the bracket and which bears on top of plate 13^a (see Figs. 3 and 6.)

Secured to the rear ends of the side rails 10 are the lower ends of upright members 14 and secured to and projecting forwardly from the upper portions of said uprights are hand rails 15, the forward portions of which 70 extend downward and their lower ends are rigidly secured to the forward portions of side rails 10.

The upper portions of the uprights 14 and the rear portions of hand rails 15 are manually engaged by an operator while the rack is being moved from one position to another.

Arranged beneath the rear ends of the side rails 10 of the base frame are castor wheels 16.

Arranged to slide freely on the upper edges 80 of the side rails 10 are the base rails 17 of a sliding frame and formed integral with and projecting upwardly from the forward ends of these sliding rails are vertically disposed plates or panels 18, preferably formed of sheet metal and which function as the side walls of the rack that receives the piles or stacks of paper.

Rigidly secured to the upper portions of 85 these side wall plates 18 are the upper ends of braces 19, which extend downwardly and rearwardly and the lower ends of said braces are secured to the rear ends of the sliding rails 17.

The ends of a horizontally disposed rod 20 90 are supported in bearings on the upper portions of the braces 19 and loosely mounted on the central portion of this rod is the forward end of a hand lever 21 that projects 95 rearwardly to a point above and between the 100

rear portions of hand rails 15 and formed integral with and projecting downwardly and rearwardly from the forward end of this hand lever is a crank arm 22.

Arranged to move freely between the side walls or plates 18 is an upright plate 23, preferably of sheet metal and projecting from the rear face thereof near its center is a web or plate 24. Pivotedly secured to the lower portion of this web 24 is the forward end of a rod 25 and the rear end of this rod is pivotally connected to the lower end of crank arm 22.

Pivotedly mounted on the forward portion of hand lever 21 is a bell crank shaped hook 26 and a notch 27 in the forward end thereof is adapted to engage a rod 28 that has its ends seated in the rear portions of side walls 18 nearer the upper ends thereof. The short arm of this hook 26 is connected by a rod 29 to a short hand lever 30 that is pivotally mounted on the rear end of hand lever 21.

Pivotedly secured to the lower ends of the uprights 14 are upwardly and forwardly projecting tubes 31 and arranged for sliding movement in the upper portion of said tubes are rods 32, the upper ends of which are pivotally connected to ears that project rearwardly from plate 23.

Adjustably mounted on the projecting portion of rod 32 is a collar 33 which may be locked to said rod by a set screw 34 and projecting from said collar downwardly and rearwardly is a bar 35 to the collar and of which is secured a ring or collar 36 that passes around tube 31.

Adjustably mounted on tube 31 a short distance in front of the ring 36 is a collar 37 that is locked to the tube by means of a set screw 38 and this collar serves to limit the upper movement of ring 36 on the tube 31 and consequently limiting the forward and upper movement of rod 32 relatively to said tube.

Arranged between the forward portions of sliding rails 17 but not connected thereto, is an angle bar 39 to the lower flange of which is secured the lower ends of a series of rods 40 and said rods project forwardly through apertures 41 formed in the lower portion of plate 23. These rods 40 function as rests upon which the papers are piled to form the stack in the feeder.

Pivotedly connected to ears that are mounted to the ends of angle bar 39 are the forward ends of links 42 and the rear ends of said links are pivotally connected to the intermediate portions of sliding bars 17.

Secured to the central portion of angle bar 39 is the lower end of a retractile spring 43 and the upper end of this spring is secured to a cross rod 44 that extends between the rear lower portions of plates 18. This spring normally exerts upward pull on cross bar 39 and the parts connected thereto.

Pivotedly connected to the central portion of cross bar 39 is the lower end of an upwardly projecting rod 45 and the upper end of this rod is pivotally connected to a link 46 and the latter being loosely mounted on cross rod 20.

Fixed on the front side of the upper portion of rod 45 is a bracket 45^a that projects a short distance above the pivot point between said rod and the link 46 and seated in said bracket 45^a is a set screw 45^b that functions as an adjustable stop for limiting the swinging movement of link 46 and the upper end of rod 45 in one direction.

In other words this adjustable set screw 80 prevents the pivot between rod 45 and link 46 from moving past center rearwardly and when the parts occupy the positions as illustrated in Fig. 2 the forward portions of the paper supporting fingers or rods 40 may swing downward so as to clear the underside of the pile of papers that has been deposited onto the pressure head within the baling chamber.

By thus permitting the rods 40 to swing 90 vertically when the pile of papers has been deposited in the pressure chamber there is no tendency of the rods to drag on the underside of the pile of papers and disturb same or pull the lowermost papers from beneath 95 the pile while the rods are being withdrawn from the baling chamber.

Secured to the upper portion of web 24 and projecting rearwardly therefrom is a finger 47 which functions as a stop to limit 100 the swinging movement of the upper end of rod 45 toward plate 23.

In the use of my improved feeding rack, hand lever 21 is swung upward and lever 30 is manipulated so as to cause notch 27 in the 105 forward end of hook 26 to engage rod 28 and when hand lever is thus positioned plate 23, fingers 40 and the various parts and connections occupy the positions as illustrated in Fig. 1 with plate 23 in a slightly inclined position and with fingers 40 inclined so that their forward ends are elevated with respect to their rear ends.

The upper portion of rod 45 bears against stop 47 and as link 46 bears against the adjustable stop 45^b said rod and link occupy the positions as illustrated in Fig. 1, with the result that the rail 39 is held at its lowermost limit of movement with the foremost ends of the rods or fingers 40 slightly elevated.

A stack of papers is now placed on the fingers 40 with the rear edges of the papers bearing against inclined plate 23 and the ends of the papers engaging the side walls or 125 plates 18.

Thus the stack of papers occupies a substantially upright position, slightly inclined toward the rear of the rack and the rack may now be moved into position to discharge the 130

stack of papers into the pressure chamber of the baling machine.

An operator manually engages the rear ends of hand rails 15 and moves the loaded rack toward the baling machine so that the 5 stack of papers, the side walls 18 and the fingers 40 that support the stack enter the baling chamber and the operator now presses the small hand lever 30 toward the rear end of hand lever 21, thereby disengaging hook 10 26 from rod 28.

The combined weight of the stack of papers on the fingers 40, together with the upward pull exerted by retractile spring 43 now swings the fingers 40 into a substantially 15 horizontal position, as illustrated in Fig. 2 and the upward movement of rod 45 bearing against stop finger 47 will exert pressure thereon so as to swing plate 23 into a vertical position during which movement rod 32 is 20 withdrawn a short distance from tube 31 until ring 36 engages against stop collar 37.

Thus the stack of papers is delivered into the pressure chamber of the baling machine 25 and to withdraw the side plates 18 and fingers 40 from their positions to the sides and beneath the stack, the operator moves the rear end of hand lever 21 downwardly with the result that plate 23, which is now in the 30 vertical position, as illustrated in Fig. 2, will bear against the stack of papers and the pressure applied to the rear end of the hand lever will react through rod 25, arm 22 and rod 20 to cause the sliding frame comprising base rails 17, side plates 18 and braces 19 to move rearwardly until the front edges of the side plates 18 are in practical transverse alignment with plate 23 and the forward ends of the rods 40 have been withdrawn through the apertures 41 until all parts of the sliding frame occupy the positions as illustrated in 40 Fig. 3.

The pivotal connection between the rod 45 and link 46 permit said rod 45 to move upwardly a short distance, thus lowering the forward ends of the rod 40 so that they will 45 not engage and drag upon the underside of this stack of papers as they are being withdrawn from position beneath said stack.

The rack is now withdrawn from the baling machine and hand lever 21 is swung upwardly, thereby restoring the various moving parts of the rack to their original or normal positions is illustrated in Fig. 1 and hook 26 is 50 manipulated to engage rod 28, thereby locking the parts of the rack in their normal positions.

One of the wheels 13 is made vertically adjustable so that one side of the rack may be raised or lowered to adjust the vertical positions of the side plates 18 relative to the pressure chamber in the press and to compensate for any irregularity on that portion of the floor immediately in front of the press and 55 over which the rack is moved while deliver-

ing stacks of papers into the pressure chamber.

Thus it will be seen that I have provided a paper feeding rack that is especially designed for use in connection with paper baling machines and which rack is relatively simple in construction, capable of being manipulated by a single operator and very effective in performing the functions for which it is intended.

It will be understood that minor changes in the size, form and construction of the various parts of my improved paper feeding rack may be made and substituted for those herein shown and described without departing from the spirit of my invention, the scope of which is set forth in the appended claims.

I claim as my invention:

1. In a paper feeding rack, a wheel supported base, a frame arranged for sliding movement on said base, which sliding frame includes a pair of side walls, a plate arranged for tilting movement between said side walls, paper supporting means arranged for sliding movement through the lower portion of said tilting plate and manually operable means for actuating said tilting plate and said sliding frame.

2. In a paper feeding rack, a wheel supported base, a frame arranged for sliding movement on said base, which sliding frame includes a pair of side walls, a plate arranged for tilting movement between said side walls, paper supporting means arranged for sliding movement through the lower portion of said tilting plate, manually operable means for actuating said tilting plate and said sliding frame and means for limiting the forward swinging movement of said tilting plate.

3. In a paper feeding rack, a wheel supported frame, a frame arranged for sliding movement on said wheel supported frame, which sliding frame includes a pair of side walls, a plate arranged for tilting movement between said side walls and paper supporting means flexibly connected to said sliding frame and projecting through the lower portion of said tilting plate.

4. In a paper feeding rack, a wheel supported frame, a frame arranged for sliding movement on said wheel supported frame, which sliding frame includes a pair of side walls, a plate arranged for tilting movement between said side walls, paper supporting means flexibly connected to said sliding frame and projecting through the lower portion of said tilting plate and a retractile spring connected to said paper supporting means.

5. In a paper feeding rack, a wheel supported frame, a frame arranged for sliding movement on said wheel supported frame, which sliding frame includes a pair of side walls, a plate arranged for tilting movement between said side walls, paper supporting means flexibly connected to said sliding frame

and projecting through the lower portion of said tilting plate, a retractile spring connected to said paper supporting means and means on said tilting plate for limiting the swinging movement of said paper supporting means.

5 6. In a paper feeding rack, a wheel supported frame, a frame arranged for sliding movement on said wheel supported frame, which sliding frame includes a pair of side walls, a plate arranged for tilting movement between said side walls, paper supporting means flexibly connected to said sliding frame and projecting through the lower portion of said tilting plate, a retractile spring connected to said paper supporting means and manually operable means for actuating said tilting plate and said sliding frame.

10 7. In a paper feeding rack, a wheel supported frame, a frame arranged for sliding movement on said wheel supported frame, which sliding frame includes a pair of side walls, a plate arranged for tilting movement between said side walls, paper supporting means flexibly connected to said sliding frame and projecting through the lower portion of said tilting plate, a retractile spring connected to said paper supporting means, means on said tilting plate for limiting the swinging movement of said paper supporting means and manually operable means for actuating said tilting plate and said sliding frame.

15 8. In a paper feeding rack, a wheel supported frame, a frame arranged for sliding movement upon said wheel supported frame, which sliding frame includes a pair of side walls, a plate arranged for tilting movement between said side walls, paper supporting means flexibly connected to said sliding frame and projecting through the lower portion of said tilting plate and manually operable means connected to said tilting plate for imparting movement to said sliding frame.

20 9. In a paper feeding rack, a wheel supported frame, a frame arranged for sliding movement upon said wheel supported frame, which sliding frame includes a pair of side walls, a plate arranged for tilting movement between said side walls, paper supporting means flexibly connected to said sliding frame and projecting through the lower portion of said tilting plate, manually operable means connected to said tilting plate for imparting movement to said sliding frame and means for locking said manually operable means to the side walls of said sliding frame.

25 10. In a paper feeding rack, a wheel supported frame, a frame arranged for sliding movement upon said wheel supported frame, which sliding frame includes a pair of side walls, a plate arranged for tilting movement between said side walls, paper supporting means flexibly connected to said sliding frame and projecting through the lower portion of

said tilting plate, manually operable means connected to said tilting plate for imparting movement to said sliding frame, means for locking said manually operable means to the side walls of said sliding frame and means for limiting the movement of said tilting plate.

30 11. In a paper feeding rack, a wheel supported frame, a frame mounted for sliding movement on said wheel supported frame, which sliding frame includes a pair of side walls, an upright plate arranged for tilting movement between said side walls, adjustable means for limiting the tilting movement of said plate, paper supporting means flexibly connected to the sliding frame and projecting through the lower portion of said tilting plate, a hand lever fulcrumed on the sliding frame and a link connecting said hand lever with the intermediate portion of said tilting plate.

35 12. In a paper feeding rack, a wheel supported frame, a frame mounted for sliding movement on said wheel supported frame which sliding frame includes a pair of side walls, an upright plate arranged for tilting movement between said side walls, adjustable means for limiting the tilting movement of said plate, paper supporting means flexibly connected to the sliding frame and projecting through the lower portion of said tilting plate, a hand lever fulcrumed on the sliding frame, a link connecting said hand lever with the intermediate portion of said tilting plate and means for locking said hand lever to said sliding frame.

40 13. In a paper feeding rack, a frame mounted for sliding movement, which frame includes a pair of side walls, an upright plate mounted for tilting movement between said side walls and paper supporting means flexibly connected to the lower portion of the sliding frame and arranged for sliding movement through the lower portion of said tilting plate.

45 14. In a paper feeding rack, a frame mounted for sliding movement, which frame includes a pair of side walls, an upright plate mounted for tilting movement between said side walls, paper supporting means flexibly connected to the lower portion of the sliding frame and arranged for sliding movement through the lower portion of said tilting plate and means including a hand lever for effecting a rearward movement of the side plates and paper supporting means relative to said tilting plate.

50 15. In a paper feeding rack, a base, a pair of wheels supporting the forward end of said base, one of which wheels is vertically adjustable, a frame arranged for sliding movement upon said base, which frame includes a pair of side walls, a plate arranged for tilting movement by the said side walls, paper supporting means arranged for sliding movement

through the lower portion of said tilting plate and manually operable means for actuating said tilting plate and sliding frame.

16. In a paper feeding rack, a wheel supported base, a frame arranged for sliding movement on said base, which sliding frame includes a pair of side walls, a plate arranged for tilting movement by the said side walls and paper supporting means arranged for sliding and tilting movement in the lower portion of said sliding plate.

17. In a paper feeding rack, a wheel supported base, a frame arranged for sliding movement on said base, which sliding frame includes a pair of side walls, a plate arranged for tilting movement by the said side walls, paper supporting means arranged for sliding and tilting movement in the lower portion of said sliding plate and means for limiting the tilting movement of said paper supporting means.

18. In a paper feeding rack, a wheel supported base, a frame arranged for sliding movement on said base, which sliding frame includes a pair of side walls, a plate arranged for tilting movement by the said side walls, paper supporting means arranged for sliding and tilting movement in the lower portion of said sliding plate, means for limiting the tilting movement of said paper supporting means and manually operable means for actuating said tilting plate and said sliding frame.

In testimony whereof I affix my signature.
MORRIS F. BERG.
